(57) **CLAIM**

The ornamental design for a false bottom tube with cap and plug, as shown and described.

DESCRIPTION

FIG. 1 is a front view of the false bottom tube with cap and plug illustrating a first embodiment of the present design, with the back view being identical;

FIG. 2 is a top view of the false bottom tube with cap and plug illustrating the present design as shown in FIG. 1;

FIG. 3 is a bottom view of the false bottom tube with cap and plug illustrating the present design as shown in FIG. 1;

FIG. 4 is a left side view of the false bottom tube with cap and plug illustrating the present design as shown in FIG. 1;

FIG. 5 is a cross-sectional view through line A-A of the false bottom tube with cap and plug as shown in FIG. 4;

FIG. 6 is a right side view of the false bottom tube with cap and plug illustrating the present design as shown in FIG. 1;

FIG. 7 is a cross-sectional view through line B-B of the false bottom tube with cap and plug as shown in FIG. 6;

FIG. 8 is a perspective view of the false bottom tube with cap and plug illustrating the present design as shown in FIG. 1;

FIG. 9 is a perspective exploded view of the false bottom tube with cap and plug illustrating the present design as shown in FIG. 1;

FIG. 10 is a front view of the false bottom tube with cap and plug illustrating a second embodiment of the present design, with the back view being identical;

FIG. 11 is a top view of the false bottom tube with cap and plug as shown in FIG. 10;

FIG. 12 is a bottom view of the false bottom tube with cap and plug as shown in FIG. 10;

FIG. 13 is a left view of the false bottom tube with cap and plug as shown in FIG. 10;

FIG. 14 is a cross-sectional view through line D-D of the false bottom tube with cap and plug as shown in FIG. 13;

FIG. 15 is a right side view of the false bottom tube with cap and plug illustrating the present design as shown in FIG. 10;

FIG. 16 is a cross-sectional view through line E-E of the false bottom tube with cap and plug as shown in FIG. 15;

(Continued)

FIG. 17 is a perspective view of the false bottom tube with cap and plug illustrating the present design as shown in FIG. 10; and,

FIG. 18 is a perspective exploded view of the false bottom tube with cap and plug illustrating the present design as shown in FIG. 10.
